UNITED STATES PATENT OFFICE

FRED A. JAMISON, OF EAST NICOLAUS, CALIFORNIA

GRAIN DRIER AND CLEANER

Application filed February 8, 1928. Serial No. 252,829.

This invention relates to apparatus for drying and cleaning grain and analogous material.

The principal objects of the invention are 5 to produce an apparatus of the above kind so constructed as to make it possible to clean and dry large quantities of material expeditiously and economically, and to produce such an apparatus which occupies a 10 comparatively small space and can be built and operated at a comparatively small expense.

A still further object is to improve grain drying and cleaning apparatus in the structural respects hereinafter particularly described and set forth in the claim.

In the accompanying drawings:—

Figure 1 is a front elevational view of a grain drier and cleaner embodying the 20 present invention, partly broken away and in section;

Figure 2 is a side elevation looking toward the right of Figure 1;

Figure 3 is a fragmentary side elevation 25 looking toward the left of Figure 1;

Figure 4 is a central vertical section of the device shown in Figure 1;

Figure 5 is an enlarged fragmentary section showing the open bottom conveyor for 30 receiving the grain from an elevator and delivering the grain in uniformly distributed manner across the feed hopper;

Figure 6 is an enlarged fragmentary detail sectional view showing the separator 35 shaker screens provided between the feed hopper and the upper drying chamber; and

Figure 7 is a sectional perspective view of the feed roller for discharging the grain from the feed hopper.

Referring more in detail to the drawings, the present invention, briefly stated, includes a suitable frame 5 constructed to provide an upright or vertical shaft having a feed hopper 6 at the top thereof, a pair 45 of superposed upright drying chambers 7 and 8 through which the material is adapted to descend when fed from the hopper 6, means located as generally indicated at 9, between the feed hopper and the upper drying chamber 7 for removing the chaff and

lighter particles from the grain as well as removing larger and smaller heavier particles from the grain before it passes into said upper drying chamber, and relay cooling shaker screens located as generally indicated at 10 between the upper and lower drying chambers 7 and 8. By thus successively passing the grain through two drying chambers, it has been found that the drying operation can be effectively accomplished in a much shorter period than attained by passing the grain through a single drying chamber.

As shown, the hopper 6 extends from side to side of the frame and is provided with a top inlet near one end as at 11. Communicating with one end of an open bottom conveyor 12 which extends from side to side of the hopper. In this way the hopper is adapted to receive the grain from an elevator, and the grain is uniformly delivered across or distributed from end to end of the hopper. As shown, the conveyor 12 embodies a suitable conveying element, preferably consisting of a shaft 13 having a projecting end provided with a drive pulley 14 and equipped with a helical conveying element or blade 15. The hopper 6 has a forwardly sloping bottom wall 16 and is provided at its forward lower portion with a plurality of discharged openings 17 through which the grain is fed positively and at a predetermined speed by means of pocketed feed rollers 18 disposed in spaced end to end relation upon a drive shaft 19 which has an end projecting beyond one end of the hopper 6 and equipped with a drive pulley 20. The cleaning and separating means located as at 9 beneath the hopper 6 and above the upper drying chamber 7 embodies a pair of shaker screens 21 and 22 provided with crank and link actuating mechanism 23, 24. Located above the forward end of the upper shaker screen 21 is an air discharge nozzle 25 arranged to discharge into the flared forward end of a wide flat and horizontally disposed discharge tube 26. The adjacent ends of the nozzle 25 and tube 26 are disposed in spaced relation respectively in front and at the rear of the hopper discharge 100

opening 17 so that as the grain is discharged from the hopper onto the upper shaker screen 21, the air discharged from the nozzle 25 will blow the chaff out through the discharge tube 26 where it may be caught and collected by any suitable means. The foraminous bottom of the upper shaker screen 21 has openings of such size as to permit the ready passage therethrough of grain of standard size, larger heavy particles being retained and ultimately being discharged at the rear end of the shaker screen 21 through a spout 27. On the other hand, the openings in the foraminous bottom of the lower shaker screen 22 are of such size as to only permit passage therethrough of heavy particles smaller than the standard size grain, and arranged beneath the shaker screen 22 is an inclined chute 28 adapted to convey these smaller particles from the apparatus or to the front thereof where they may be suitably collected. It is thus apparent that substantially the only remaining material will be standard size grain upon the screen 22, which will be ultimately discharged at the rear end of the shaker screen 22 or to a forwardly inclined chute 29. An open bottom conveyor 30 is arranged horizontally beneath the chute 28 in position to receive the standard sized and cleaned grain from the chute 29, and this conveyor 30 extends from side to side of the vertical shaft so as to deliver the grain across the top of the upper drying chamber 7. From the open bottom conveyor 30, the cleaned grain is discharged and uniformly distributed at the top of the drying chamber 7, through which said grain is adapted to descend by gravity, as will be apparent.

40 Arranged horizontally in each of the drying chambers 7 and 8 and extending from side to side of the latter are a plurality of staggered foraminous or perforated air nozzles 31 through which heated air is discharged against the descending grain for drying the latter more or less. These air discharge nozzles receive their supply of hot air as will be presently described, and as clearly shown in Figure 4, these nozzles 45 are of triangular form in cross section so as to present downwardly diverging walls and act as baffles for deflecting the falling grain and spreading it throughout the area of the drying chamber for most effective action of 50 the heated air thereon. The chambers 7 and 8 are provided at the front and rear with foraminous or screened walls as at 32 to permit the free exit of the air as it is supplied from the nozzles 31 into the chambers 7 55 and 8.

The cooling shaker screens 33, located one above the other as generally indicated at 60, are provided with suitable crank and link actuating mechanism 34, 35, and the openings in the foraminous bottom walls of these

shaker screens are of sufficient size to permit the standard sized grain falling therethrough from one to the other and from the lower shaker screen 33 into the lower drying chamber 8. However, the shaker screens 33 70 act to retard the descending grain and retain it for a period of cooling while being shaken and relayed from the upper drying chamber to the lower drying chamber. Such small amount of particles which are larger 75 than and may have adhered to the grain until after passing through the upper drying chamber 7 may find their way off of the opposite ends of the screens 33 for being discharged from the apparatus through the 80 spouts 36.

It is particularly noted that when the chaff is blown from the grain through the discharge tube 26, a small amount of moisture will be initially extracted from the grain 85 and when the grain passes through the upper drying chamber 7, a further extraction of moisture takes place with what moisture as remains on the surface of the grain being uniformly spread over the surface of the 90 grain as it is subsequently shaken in the screens 33. It is thus evident that when the grain is subsequently submitted to a further 95 drying operation in the lower drying chamber 8 the drying will be thoroughly completed so that the grain will be in proper condition for storage, milling or the like when discharged from the lower heating or drying chamber 8.

The lower drying chamber 8 is provided 100 with downwardly converging bottom walls 37 providing a discharge opening 38 adjacent their lower meeting edges through which the dried grain may pass from the lower drying chamber 8, the flow of the 105 grain being suitably controlled by an adjustable gate 39 associated with the opening 38. A suitable spiral conveyor 40 is disposed beneath the opening 38 transversely of the apparatus for conveying the dried grain to a desired point of discharge or disposal. As shown, the various driven parts may be suitably belted or geared together for being driven from a common power shaft 41 provided with a drive 110 pulley 42.

Located at one side of the upright shaft 115 is a vertical manifold 43 connected at its lower end to a pipe 44 leading from a suitable source of hot air under pressure. Obviously, this pipe 44 may lead from a blower which receives its supply of air from an air heating furnace, the proper temperature of the air being maintained in connection with the observation of a thermometer 120 125 provided upon the manifold 43. The manifold 43 is provided with numerous branch outlet pipes 46, each of which leads to one of the air nozzles 31 and is provided with a suitable regulating valve 47 for control- 130

ling the flow of air to and through the nozzle 31. In a like manner, the nozzle 25 receives its supply of air from the manifold 43 as is shown clearly in Fig. 2. The manifold 43 is open at its upper end so that excess hot air may be discharged therefrom, said end of the manifold being equipped with a valve 48 for use in regulating the discharge of air from the manifold and consequently regulating the air pressure therein.

Obviously, by properly timing the speed of operation of the several parts such as the feed rollers 18, conveyors 12 and 40, and shaker screens 21, 22 and 33, the speed of operation may be properly adjusted to insure thorough drying of the grain while at the same time carrying out the drying operation in a most expeditious manner.

Minor changes may be made without departing from the spirit and scope of the invention as claimed.

What I claim as new is:—

A grain cleaner and drier comprising an upright shaft through which the grain passes during the cleaning and drying operation, said shaft having a feed hopper at its upper end, vibrating screens below said hopper, means for blowing a current of air over the grain during the screening thereof to separate the chaff, means for discharging the removed chaff, a heating and drying chamber below said screens, into which the separated grain is discharged and distributed, vibrating screens below said chambers upon which the partially heated and dried grain is discharged, and by which the grain is subjected to air cooling, a second heating and drying chamber below said screens through which the grain is passed and means for discharging the grain from the bottom of the shaft.

In testimony whereof I affix my signature.

FRED A. JAMISON.
